United States Patent Office

Des. 234,017
Patented Dec. 31, 1974

234,017

PLASTIC SPOON

Hubert E. Christian and David W. Lee, Phoenix, Ariz.,
assignors to Dart Industries, Inc., Los Angeles, Calif.

Filed May 21, 1973, Ser. No. 362,357

Term of patent 14 years

Int. Cl. D7—03

U.S. Cl. D7—138

FIG.—1

FIG.—5

FIG.—2

FIG.—6

FIG.—3

FIG. 1 is a top plan view of a plastic spoon showing our new design;
FIG. 2 is a bottom plan view thereof;
FIG. 3 is a side elevational view thereof;
FIG. 4 is a front end view thereof;
FIG. 5 is a rear end view thereof; and,
FIG. 6 is a cross-sectional view thereof in an enlarged scale, taken along the line 6—6 of FIG. 2.

We claim:

The ornamental design for a plastic spoon, substantially as shown and described.
